(57) **CLAIM**

The ornamental design for a head for mobile service robot, as shown and described.

DESCRIPTION

1. A head for a mobile service robot
- 1.1 is a front perspective view of my new design for a mobile service robot
- 1.2 is a front side elevation view of Figure 1.1
- 1.3 is a back side elevation view of Figure 1.1
- 1.4 is a left side elevation view of Figure 1.1
- 1.5 is a right side elevation view of Figure 1.1
- 1.6 is a top side plan view of Figure 1.1
- 1.7 is a bottom side plan view of Figure 1.1
